UNITED STATES PATENT OFFICE

RICHARD W. ERICSON, OF CHICAGO, ILLINOIS

DESIGN FOR A DESK OR ANALOGOUS ARTICLE OF FURNITURE

Application filed February 16, 1931. Serial No. 38,691. Term of patent 3½ years.

To all whom it may concern:

Be it known that I, RICHARD W. ERICSON, a citizen of the United States, residing at Chicago, in the county of Cook and State of Illinois, have invented a new, original, and ornamental Design for a Desk or Analogous Article of Furniture, of which the following is a specification, reference being had to the accompanying drawings, forming part thereof:

Fig. 2 is a perspective view of the front side of a desk showing my new design.

I claim:

The ornamental design for a desk or analogous article of furniture, as shown.

RICHARD W. ERICSON.
